UNITED STATES PATENT OFFICE.

WILLIAM C. RUOPP, OF UPPER SANDUSKY, OHIO, ASSIGNOR TO NATIONAL STEAM PUMP COMPANY, INC., OF UPPER SANDUSKY, OHIO, A CORPORATION OF OHIO.

IGNITER.

1,145,269.

Specification of Letters Patent.

Patented July 6, 1915.

Application filed October 29, 1913. Serial No. 798,098.

To all whom it may concern:

Be it known that I, WILLIAM C. RUOPP, a citizen of the United States of America, residing at Upper Sandusky, in the county of Wyandot and State of Ohio, have invented new and useful Improvements in Igniters, of which the following is a specification.

This invention relates to improvements in igniters for internal combustion engines and has particular application to an igniter of the flame heated type.

In carrying out the present invention, it is my purpose to provide an igniting device which will be carried by the cylinder head and extend into the same in the path of the incoming live fuel so that the latter will be ignited to propel the engine piston.

It is also my purpose to provide an igniter which may be initially heated in a relatively short time and which will embrace the desired features of simplicity, efficiency and durability.

With the above and other objects in view, the invention consists in the construction, combination and arrangement of parts hereinafter set forth in and falling within the scope of the claim.

In the accompanying drawing; Figure 1 is a fragmentary side elevation of a horizontal cylinder stationary engine equipped with an igniter constructed in accordance with the present invention, part of the cylinder being shown in longitudinal section. Fig. 2 is an enlarged longitudinal sectional view through the igniter.

In the present instance, I have shown my invention as applied to a two cycle internal combustion engine of the stationary type. I wish it to be understood, however, that my invention in its useful application is not limited to this particular type of engine, as the same may be employed in conjunction with four cycle and other engines.

Referring now to the accompanying drawing in detail, the numeral 1 designates the cylinder of a stationary internal combustion engine, such cylinder having a water jacket 2 and a head 3. Mounted for reciprocation within the cylinder 1 is a piston 4 controlling an air inlet port 5 formed in the side wall of the cylinder and adapted to establish communication between the latter and the crank case of the engine, the piston in its rearward movement compressing the air

within the crank case so that when the port 5 is uncovered by the piston such air will be delivered to the cylinder. Also formed in the side wall of the cylinder at a point diametrically opposite the passage 5 is an exhaust port 6 controlled by the piston 60 and designed to be uncovered thereby to permit the escape of the burnt gases from the cylinder. Extending through the side wall of the head 3 of the cylinder is a fluid inlet nozzle 7 by means of which live fuel is forced into the cylinder, such nozzle being preferably connected up with a source of pressure so that the liquid fuel will be delivered to the cylinder under pressure.

Formed in the top of the cylinder head is an opening 8 through which is passed my improved igniter composed, in the present instance, of a hollow cylindrical body 9 having a closed end 10 projecting into the cylinder in the path of the fuel issuing from the nozzle 7, and an open end 11 equipped with an outwardly projecting annular flange 12 resting upon the adjacent portion of the cylinder head and suitably secured thereto.

The numeral 13 designates a cup-shaped cap having the side wall thereof suitably secured to the marginal edge of the flange 12, while 14 designates a partition mounted within the body 9 and extending into the same and terminating short of the closed end 10 of such body, the edges of the partition engaging the inner wall of the body at diametrically opposite points. Formed in the end wall of the cap 13 upon one side of the partition 14 is an inlet opening 15, while an outlet opening 16 is formed in the side wall of the cap at the opposite side of the partition.

From the foregoing description taken in connection with the accompanying drawing, the construction, mode of operation and manner of employing my invention will be readily apparent. When it is desired to initially heat the igniter, a torch or the like is placed within the cap 13 through the opening 15 and the heat and flame of such torch pass into the body 9 at one side of the partition 14 around to the other side of such partition and out through the opening 16, thereby heating the end of the body within the cylinder to a relatively high temperature, the inner end wall of the body be-

ing preferably rounded off as at 17 to facilitate the heating action. In the operation of the engine, air under pressure is delivered to the engine cylinder through the passage 5, when the latter is uncovered by the piston, and the piston in its forward movement compresses such air to a high degree. When the air is thus under compression, the fuel is delivered into the cylinder by the inlet 10 nozzle 7 and impinges upon the body of the igniter, incident to the latter being in the path of the fuel, such fuel being thereby vaporized and commingles freely with the compressed air so as to form a highly explosive mixture which is fired or exploded 15 by the heat from the igniter and the adjacent walls of the cylinder head in addition to the heat of compression. The gases, exploding, drive the piston inwardly on the power stroke, the power being taken from 20 the piston through the agency of a pitman and crank shaft or in some other suitable manner, as is readily apparent to those skilled in the art. When the piston reaches its limit of inward movement, the exhaust 25 port 6 is uncovered so that the burnt gases escape to the atmosphere, while the passage 5 is also uncovered to deliver a fresh charge of air to the cylinder at which time the above 30 operation is repeated.

It will be seen that I have provided an igniter by means of which the oil entering the cylinder is thoroughly vaporized and subsequently mixed with the air under com-

pression in such manner as to produce a 35 highly explosive gas.

While I have herein shown and described one preferred form of my invention by way of illustration, I desire to have it understood that I do not limit or confine myself 40 to the precise details of construction herein described and delineated, as modification and variation may be made within the scope of the claim without departing from the spirit of the invention. 45

I claim:

An igniter for internal combustion engines comprising a cylindrical body projecting into the cylinder of the engine in the path of the gases, a partition arranged 50 within said body centrally thereof and terminating short of the inner end of the body whereby communicating longitudinal chambers are formed, a circumferentially extending flange formed on the outer end of said 55 body, a cup-shaped cap secured to the marginal edge of said flange and closing the outer end of said body, said cap being formed with an inlet opening at one side of the partition and an outlet opening at the 60 opposite side of such partition.

In testimony whereof I affix my signature in presence of two witnesses.

WILLIAM C. RUOPP.
